DESIGN FOR AN AUTOMOBILE RADIATOR CAP ORNAMENT

Albert Sebek, Cicero, Ill.

Application September 8, 1936, Serial No. 64,760

Term of patent 3½ years

To all whom it may concern:

Be it known that I, Albert Sebek, a citizen of the United States, residing at 2303 South 62nd Avenue, Cicero, in the county of Cook and State of Illinois, have invented a new, original, and ornamental Design for an Automobile Radiator Cap Ornament, of which the following is a specification, reference being had to the accompanying drawing, forming part thereof.

Fig. 1 is a side elevation of a radiator cap embodying my design;

Fig. 2 is a plan view of same;
Fig. 3 is a front elevation of same;
Fig. 4 is a rear elevation of same, and
Fig. 5 is a cross-section taken on line 5—5 of Fig. 1.

I claim:

The ornamental design for an automobile radiator cap ornament as shown.

ALBERT SEBEK.
